UNITED STATES PATENT OFFICE.

WILLIAM B. STERRIT, OF PITTSBURG, PENNSYLVANIA.

MACHINE FOR MAKING GREEN-SAND CORES.

SPECIFICATION forming part of Letters Patent No. 470,517, dated March 8, 1892.

Application filed December 10, 1890. Serial No. 374,186. (No model.)

To all whom it may concern:

Be it known that I, WILLIAM B. STERRIT, a citizen of the United States, residing at Pittsburgh, in the county of Allegheny and State 5 of Pennsylvania, have invented certain new and useful Improvements in Machines for Making Green-Sand Cores; and I do hereby declare the following to be a full, clear, and exact description of the invention, reference 10 being had to the accompanying drawings, which form part of this specification.

This invention has relation to machines for making green-sand cores for hollow castings, and relates particularly to machines for making 15 cores to be used in casting journal-boxes and the like.

The object of this invention is to provide a machine for compressing the green sand within a core-box and upon a suitable core-bar, 20 thereby obviating the necessity of preparing the core by hand.

In the machine embodying my invention the core-box adapted to contain the core-bar is constructed with movable side walls or a 25 movable bottom and is provided with means for forcing the sides or the bottom, as the case may be, inwardly and upon and against the body of green sand from which the core is to be formed. Means are also provided for 30 the displacement or temporary removal of certain portions of the core-box, so as to obtain access to the interior of the same for the purpose of filling in the sand preparatory to completing the core and for the purpose of 35 allowing the core to be removed after completion.

My invention consists in the novel construction, combinations, and arrangements of parts hereinafter described.

40 In the following specification I shall limit myself to a specific description of a machine for forming green-sand cores for journal-boxes, it being understood, however, that the same machine or its essential parts may be 45 employed in forming green-sand cores for a great variety of hollow castings.

Referring to the accompanying drawings, Figure 1 is a vertical longitudinal section of a machine for forming green-sand cores for 50 journal-boxes. Fig. 2 is a vertical transverse section of the same looking to the right of Fig. 1. Fig. 3 is a horizontal section on the

line X X of Fig. 2. Fig. 4 is a perspective view of the slides which embrace the core of the dust-chamber. Fig. 5 is a sectional view 55 of a detail. Fig. 6 is a detail perspective view of the catch for holding the swinging arch in position. Fig. 7 is a transverse sectional view looking to the left of Fig. 1 and showing the vertical side walls drawn out; and Fig. 8 is a 60 perspective view of the core-bar, showing the core-bar and the end plates on which it is supported.

In the machine shown in Figs. 1, 2, and 3 the core-box is arranged so that the top of 65 the core is uppermost.

When the core-box is arranged as shown in Figs. 1, 2, and 3, the sand is compressed by the inward movement of the sides of the box.

Referring now specifically to the construction shown in Figs. 1, 2, and 3, A designates a casting constituting the bottom of the core-box and having its upper surface shaped to coincide or correspond with the contour which it is desired to give to the bottom of 75 the core. The casting A is supported at its ends by substantial standards B B, which constitute the end frames of the machine and are secured to a base plate or frame C.

D is a strong metallic arch, which spans 80 the space between the two end frames B B and rests at its ends upon the tops of said frames. The arch D is pivotally attached to one of the frames B, so that it may be swung around with the top plate of the core-box 85 which it supports, and when in position is secured at its other end to the other of the frames B by a lug b on the frame, which enters a notch d in the arch. The top plate E of the box is supported by the arch upon the 90 lower end of a swiveled screw F, which passes through a threaded hole in the center of the arch and is provided with a hand-wheel f, by turning which the top plate E may be raised and lowered. When the plate E is in position, it is supported at its ends only upon 95 vertical stationary end sections of the core-box, which are secured to the frame of the machine and rest upon the bottom of the core-box, and the inner surface of the plate is 100 shaped to conform with the shape of the finished core. These stationary end sections, of which there are four, are clearly shown in the sectional view, Fig. 3, and they consist of

105

metallic sections of L shape in horizontal section, the shorter side of each section being bolted to the end frames B B and the longer side of each section being in line with the removable end plates g g of the core-bar when the latter is in position in the core-box. The stationary end sections are lettered H' in Fig. 3 and serve, as before stated, to support the plate E at its ends.

- 10 G designates the core-bar, which is supported within the core-box by means of flanged end plates g g, mortised for the reception of the tenons on the ends of said bar, said tenons being pierced laterally to receive wedge-shaped fastening-keys g' g'. The core-bar G is of tapering form or wedge-shaped, so as to facilitate its withdrawal from the core, and is formed with tapering enlargements g² g², upon which are fitted and secured by suitable 20 keys the perforated plates h h. The end plates g g rest upon those portions of the bottom plate of the core-box which extend out beyond the limits of the core and are removable with the core-bar, the said core-bar with 25 the end plates attached thereto being shown apart from the core-box in Fig. 8 of the drawings.

H H designate the movable sides of the core-box, which rest and move upon the bottom plate of the core-box, and are flanged upon their upper and lower edges, as shown at h' h', so as to give them wide bearings, which will prevent irregular movement or sagging. On the outer faces of the sides H 30 H there are formed lugs K K, through which pass pins k k, connecting thereto the upper ends of the bent levers L L, through which the sides of the box are moved inwardly to compress the core-sand and outwardly to release the core. The upper ends of the levers L L impinge upon the sides of the core-box and move in frictional contact therewith, and the point of contact is armed with a beveled steel block dovetailed into the ends of the 40 levers, similar blocks being dovetailed into the sides H H of the box. The levers L L are fulcrumed below the bottom plate of the core-box upon horizontal shafts L' L', supported by or having their bearings in brackets L² L², depending from the bottom of the core-box. These levers L L are coupled at their lower ends to toggle-arms M M, having their inner ends pivotally connected to a nut m, that is secured to a vertically-reciprocating frame N, through which passes the operating-lever O, which is pivoted at o to the frame of the machine. When the lever, which is or may be secured to the frame N by a transverse pin, is lifted, and with it the inner 50 ends of the toggle-arms, the levers L L are drawn inwardly at their lower ends and outwardly at their upper ends, thus moving the sides of the core-box away from the core. The descent of the lever N forces the sides of the core-box inwardly and compresses the sand to the required degree to form the core.

The frame N is guided in its vertical travel

by means of a pin N', rising from its upper portion and passing through a hole in a bridge N² connecting the brackets L² L².

P designates a narrow space formed at one end of the core-box by the slides P' P² P³ and intended to receive the dry-sand core, which forms the dust-chamber at the end of the journal-box. These slides fit in suitable grooves p' p² in the sides of the core-box, such grooves being of sufficient depth to give the slides a bearing in the sides when the latter are drawn outwardly to their fullest extent. The slides P' P² are connected together at their outer edges, so as to form an inclosed space, in which inclosed space is fitted, previously to packing the sand, a dry-sand core, which serves when the casting is made to leave a space that constitutes the dust-chamber of the journal-box, 80 and they are supported from above by means of a lever q and connecting-rod q' attached to the arch D at q². The top plate E of the core-box is transversely slotted at r r for the passage of the slides P' P². The plate P' rests within the core-box upon shoulders formed at the bottom of its grooves p' the semicircular recess in the under part of the plate P', thus coinciding with the curvature in the bottom of the core-box. The plate P² rests upon the plate P³, which rises from below the bottom of the core-box through a transverse slot r', and is raised and lowered by means of a lever S, connected thereto and pivoted at s to the bottom of the core-box.

The operation of the machine above described is as follows: The plates P' P² P³ being withdrawn from the cavity of the core-box and the top plate E raised by means of the screw F, the arch D is swung around to one side, carrying with it the top plate E and its appendages. The core-bar, with its attachments, including the dry-sand core that fits between the plates P' P² P³, is now placed in position and the lever O raised, so as to draw outwardly the sides of the box. The green sand is now filled in in sufficient quantity and the arch swung around, bringing the top of the box into place. The latter is now lowered and the slides P' P² P³ pushed home. The lever O is now lowered or forced downwardly and the sides of the core-box forced inwardly under great pressure, thus packing the sand tightly around the core-bar and into all the spaces of the core-box cavity. The plates P' P² P³ are then withdrawn, the sides of the box drawn outwardly, and the top plate shifted, thus exposing the perfect core, which may be then lifted by means of the end plates and inserted into the mold.

Having described my invention, I claim—

1. In a machine for forming green-sand cores, the combination, with a supporting frame, of a core-box having a stationary bottom mounted on said frame, laterally-movable side walls supported and sliding on said bottom plate, a movable top plate supported from said frame and covering and closing the top of the core-box, and an adjustable supporting

device by which said top may be raised and lowered and shifted or moved horizontally, all constructed and arranged substantially as described.

5 2. In a machine for forming green-sand cores, the combination, with a suitable supporting-frame, of a core-box having a stationary bottom plate, vertical side walls having stationary end sections and laterally-movable intermediate sections, and a detachable top plate, which covers and closes the top of the core-box and is vertically and horizontally movable, and means for supporting said top plate from the main frame and for raising and lowering the same, substantially as described.

15 3. The combination, with a core-box constructed and adapted for the formation of cores for journal-boxes or other hollow castings, of a core-bar supported in said box, a dry-sand dust-chamber core, and vertical slides in said box between which said core is supported, substantially as described.

20 4. The combination, with a core-box con-

structed and adapted for the formation of cores for hollow castings, of a dry-sand core 25 consisting of a flat section of compressed dry and baked sand, having a central opening, and vertical slides seated in grooves in said core-box and embracing said dry-sand core, substantially as described.

30 5. In a machine for forming green-sand cores for hollow castings having dust-chambers, the combination, with the core-box and with a dry-sand core for forming a dust-chamber, of the slides P' P² P³, supported in grooves 35 in the sides of said core-box and embracing the dry-sand core, and the levers S and q, connected to said slides and pivoted to the frame of the machine, substantially as described.

In testimony that I claim the foregoing I 40 have hereunto set my hand this 6th day of November, 1890.

WILLIAM B. STERRIT.
